UNITED STATES PATENT OFFICE.

SAMUEL S. SADTLER, OF SPRINGFIELD TOWNSHIP, MONTGOMERY COUNTY, PENNSYLVANIA, ASSIGNOR TO AMIESITE FOUNDATION COMPANY, A CORPORATION OF DELAWARE.

CONSTRUCTION OF ROADS HAVING A FOUNDATION COURSE OF SAND.

Application filed August 28, 1926. Serial No. 132,137.

My invention relates to the construction of roads, particularly in sandy soils and it is the aim and purpose of my invention to utilize such sand as the foundation course of 5 the roadway.

A further object of my invention is to simplify and reduce the cost of building satisfactory roads through a sandy soil by rendering the road foundation composed of 10 such sand sufficiently rigid to prevent lateral movement of the sand after the road is constructed.

A further object is to provide a road construction wherein sand is used as the main 15 and essential constituent of the foundation course and wherein such sand is protected from the action of water thereon and from liability of being shifted laterally under the load of traffic thereon.

20 A further object of my invention is to provide a road construction wherein the load of moving traffic on the surface thereof will be transmitted to a foundation course of normally shifting consistency, but over a 25 relatively large area of said foundation course, by two courses of different flexible fabrics between the foundation course and the top or surface course and operative to prevent any lateral or transverse movement 30 of the material comprising the foundation course.

Other objects of my invention will appear in the specification and claims below.

In the drawings forming a part of this 35 specification and in which the same reference characters are used throughout the various views to designate the same parts.

Fig. 1 is a somewhat diagrammatic view 40 in transverse cross-section, of a road embodying my invention with the various courses or layers employed in the construction spaced one above the other and Fig. 2 is a similar cross-sectional view of the completed roadway.

45 In these drawings a little more than one-half of a complete cross-section of the road is indicated in the drawings it being understood that both sides of the road are alike.

50 Nor do the drawings strictly indicate the relative sizes of the various courses of the road. The thickness of certain courses is greatly exaggerated for the purpose of making the construction clear in the drawings.

This will be referred to again below with more particularity.

55 In making a road through a sandy soil 1, I first bring the surface of the soil to the top 2' of the foundation level by dragging or excavating to provide a foundation 2 of sand having the necessary grade and crown. 60 The foundation 2 of sand having been crowned and graded I then preferably form on opposite sides of the foundation 2 suitable trenches 3 for the reception of the curbing 4 which is preferably of concrete cast in 65 the usual manner in the trenches 3 between or against wooden molding boards which hold the wet concrete in form until it has set, and each curbing 4 may be provided with a gutter 5 cast integral therewith. The curbing 4 provides a retaining wall which prevents lateral movement of the said foundation 70 2.

75 In bringing the top 2' of the foundation level to proper grade and crown, I may have inserted into the sand suitable stakes 6 (preferably creosoted), the tops of which are positioned so as to indicate the level or plane to which the top of the foundation should be brought. If, however, such stakes were 80 not used in the making of the foundation, then I may insert such stakes 6 (preferably creosoted) into the crowned foundation driving them down until the tops thereof are flush with the top surface 2' of the foundation course 2. In either case I preferably position a row or series of stakes 6 relatively close to the curbing 4 so that a subsequent course 85 of the road may be secured thereto along the sides of the road adjacent the curbing as 90 will be referred to again below.

95 In order to compact the sand of the foundation course 2, I preferably wet it with water to make the course damp to a depth of from 6 to 10 inches. Over the surface or top 2' of this damp compacted foundation course 2, I then lay a protective course 7 composed of strips or pieces or sheets 7' of a coarse textile fabric, which may be the jute bagging in which lime and similar materials are usually contained. The adjacent edges 100 of these sheets 7' of textile fabric are overlapped to shed water as clearly indicated in the drawings. This protective fabric course 7 when treated as described below, is to prevent water from above from entering the 105

sand foundation after the road is completed and to assist in distributing the load of traffic over a large area of the foundation course. After the textile fabric has been 5 thus placed over the surface 2' of the foundation, I apply to the upper surface thereof a course or layer or sprinkling or painting 8 of asphaltic material, such as asphaltic road oil, which may be heated to render it 10 quite liquid and capable of being absorbed by the fabric. I preferably provide more of this thin liquid than can be absorbed by the fabric so that this asphaltic oil will penetrate and pass through the coarse fabric and 15 become mixed with the sand below the fabric. After the oil has been thus applied, I may sprinkle over the upper surface of the bagging a small amount or layer or course of sand 9 to absorb the excess oil above the 20 fabric course 7. When this has been done and the roadway is completed there will be above and below the fibrous fabric 8 a comparatively thin or light course 89, composed of sand intermixed with asphaltic oil.

25 On top of this course 89, on the fabric 8, I then lay a course 10 of fabricated metal material, such as galvanized chicken wire, of preferably about one inch mesh and I secure it to the posts or stakes 6 by any 30 suitable fastening means 11, such as nails, tacks or staples. In so securing the wire mesh fabric 10 to the stakes I stretch it so that it will lie smoothly down on the upper surface of the coarse fabric 8 or the thin 35 course 89 of asphalt and sand thereon. This chicken wire is obtainable in strips of suitable width and in laying it upon the foundation, as above described, I preferably bind the edges of adjacent strips firmly together 40 with wire.

The length of each strip of wire fabric is preferably somewhat longer than the distance between opposite curbs so that the ends thereof may be bent and lapped up 45 against the curbing 4. In this way the wire fabric 10 and the fibrous fabric course 7 are securely attached or anchored to the posts 6 in the foundation 2 and bed of the roadway.

50 Although the wire mesh fabric 10 is preferably a galvanized wire fabric, I prefer to make it certain that it is thoroughly protected from corrosion. I, therefore, over the wire fabric, next preferably lay or spread or sprinkle a coating or course 12 of asphaltic material, such as asphaltic oil or liquid asphalt so as to thoroughly coat the strands of the wire mesh fabric with asphalt. In Fig. 2 of the drawing, this course 12 of asphaltic material appears as resting on or above the 55 top of the wire mesh fabric 10 but, of course, in practice, the asphaltic material will settle down into the wire mesh fabric 10, and layers 89 on each side thereof. In the wire fabric the mesh is preferably of about one inch.

60 65 Moreover, the size of the nails and the size

of the stakes 6 are also exaggerated for the purpose of clearness.

After this course or layer of asphalt 12 has been thus placed on the wire mesh fabric 9, I then lay thereon a surface course 13, 70 preferably of amiesite. This course of amiesite is preferably made up of two layers, compressing the lower layer 13' of larger broken stone, preferably that which would not pass through a one inch screen and an upper course 13'' of finer broken stone all 75 the stones thereof being thoroughly coated on all sides with a heavy asphaltic material.

After the surface course 13 has been placed, it is preferably given a thin dusting 80 or coating 14 of cement, sand or other material and rolled with a heavy roller, thus compacting the whole roadway and bringing it to the level of the inner edge of the gutters 5 when the curbing 4 is provided 85 with gutters.

A road constructed in the manner above set forth and having a surface course of amiesite or similar black surfacing material operates under traffic to transmit the load 90 of traffic from the surface course 13 by the two fabric courses 10 and 7 to the sand foundation 2 but in this transmitting the load, they distribute it over a relatively wide area of the sand foundation course so that the sand 95 or foundation course is not pressed or moved transversely or laterally but offers a firm rigid support for the traffic or load on the road.

When desirable I may treat the sand 100 foundation 2 chemically before placing thereon the bagging course 7. Thus instead of compacting the sand by sprinkling water thereon, I may sprinkle it with a liquid mixture of silicate of soda, sulphuric acid and 105 water to compact it and to make the sand more rigid and water-resisting. I may form the liquid by mixing substantially 10 volumes of a commercial grade of silicate of soda, diluted with 90 volumes of water, with 110 a 10% aqueous solution of sulphuric acid. The amount of sulphuric acid to the sodium silicate solution being substantially as 1 to 4.

When this solution dries it becomes insoluble and the sand foundation will be provided with a crust downwardly into the foundation course from the surface thereof.

In the road above constructed I have thus provided two courses of different materials for distributing the load of the traffic on the 115 road over a large area with the sand foundation. The course 7 of bagging preserves the surface 2' on the sand foundation stationary. That is to say, the traffic does not cut into it. The textile fabric holds the surface stationary, although of itself the bagging is very flexible and the wire mesh fabric 10 distributes the load over it. The course 10 of fabricated wire is more rigid 120 and has great tensile strength. It is secure- 125 130

ly anchored to the posts 6 as above described but is prevented from sinking into the sand under the load on the surface by the fabric course 7.

5 The wire mesh fabric therefore substantially rests on a sand foundation course which virtually has a tough inextensible upper surface, formed by the textile fabric course, on which the wire mesh fabric lies, 10 and the wire mesh fabric spreads and distributes the load of traffic over a relatively large area of sand foundation made firm by the textile fabric course.

Having thus described my invention, what 15 I claim and desire to protect by Letters Patent of the United States, is:

1. A roadway comprising a foundation course of sandy soil, retaining walls at the sides of said foundation course to prevent 20 lateral movement of the sand of said foundation course, stakes driven into said foundation course and having their top surface flush with the top of said foundation course, sheets of coarse woven textile fabric having 25 their adjacent edges overlapped to shed water laid on the top of said foundation course, strips of reticular metal fabric laid on said textile fabric, fastening means securing said textile fabric and said metal fabric to the 30 tops of said posts, the top surface of said textile and the metal fabric being coated with a surface of liquid asphaltic material, and a surface course of stone aggregate bound together with asphaltic material sup- 35 ported on said reticular metal fabric.

2. A roadway comprising a foundation course composed of sandy soil, a course of jute bagging coated with liquid asphaltic material lying on the top of said sand foundation, strips of open mesh metal fabric lying 40 on said fibrous material and coated with said liquid asphaltic material, and a surface

course of stone aggregate bound together with asphaltic material supported on said metal fabric, the stone aggregate in said 45 surface course and adjacent said metal fabric being of a size larger than the size of the mesh in said metal fabric.

3. A roadway comprising a foundation course composed of sandy soil, lime and water and having a series of stakes therein extending along the roadway near the side edges thereof, a fibrous course comprising sheets of coarse woven jute fabric on the surface of said foundation course with their 55 adjacent edges overlapping to shed water and impregnated with liquid asphaltic material, strips of open mesh wire fabric lying on said jute fabric course and coated with liquid asphaltic material, the adjacent edges 60 of said wire mesh fabric being secured together and means to secure said wire fabric and said jute fabric course to the top ends of said stakes, and a surface course on said metal fabric comprising stone aggregate 65 bound together with asphaltic material.

4. A roadway comprising a foundation course of sand wetted and compacted with a mixture of silicate of soda, sulphuric acid and water, a course of coarse woven textile 70 fabric impregnated with a liquid asphalt lying on said sand foundation, an open mesh metal fabric lying on said asphalt coated textile fabric course, and a surface course of stone aggregate, the stones of which are 75 coated and bound together with an asphaltic material, the stone aggregate in said course adjacent said metal fabric being of a size larger than the size of the mesh in said metal fabric.

In witness whereof, I have hereunto set my hand this 26th day of August, 1926.

SAMUEL S. SADTLER.
